(57) **CLAIM**

The ornamental design for a single-axis solar tracker bearing adapter, substantially as shown and described.

DESCRIPTION

FIG. 1 is a top right perspective view of a single-axis solar tracker bearing adapter showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top right perspective view of a single-axis solar tracker bearing adapter showing the claimed design;

FIG. 10 is a bottom rear perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

Portions of the single-axis solar tracker bearing adapter that are not shown form no part of the claimed design.

The dashed lines in the figures show portions of the single-axis solar tracker bearing adapter that form no part of the claimed design.
